CLAIM

The ornamental design for an air freshener device, as shown and described.

DESCRIPTION

FIG. 1 is a front perspective view of an air freshener device embodying the present invention;

FIG. 2 is an end view of the air freshener device, the opposite end view being identical;

FIG. 3 is a side view of the air freshener device, the opposite side view being identical;

FIG. 4 is a top plan view of the air freshener device;

FIG. 5 is a bottom view of the air freshener device; and,

FIG. 6 is an exploded perspective view of the air freshener device.
